UNITED STATES PATENT OFFICE.

FREDERICK GEOFFREY LEES JOHNSON, OF WESTMINSTER, LONDON, ENGLAND,
ASSIGNOR TO VICKERS, LIMITED, OF WESTMINSTER, LONDON, ENGLAND.

SHELL-FUSE.

1,313,298.

Specification of Letters Patent. Patented Aug. 19, 1919.

Application filed November 11, 1918. Serial No. 262,056.

To all whom it may concern:

Be it known that I, FREDERICK GEOFFREY LEES JOHNSON, a subject of the King of Great Britain, residing at Vickers House, 5 Broadway, Westminster, in the county of London, England, have invented certain new and useful Improvements in or Relating to Shell-Fuses, of which the following is a specification.

10 This invention relates to shell fuses of the time type ignited on firing the shell from a gun, and has for its chief object to render the fuse independent of atmospheric or ballistic conditions. 15 According to this invention the fuse is so constructed as to be maintained gas tight throughout the combustion of the slow-burning composition during the flight of the shell, which composition forms a seal 20 until the combustion has advanced sufficiently to break through and ignite the shell charge. Owing to the complete internal combustion the fuse is shielded from external influences and its action is thereby rendered more reliable.

According to one construction embodying this invention the fuse body carries a plug screwed into one end of the body, the other end of which is solid, the plug carrying a 30 column of slow-burning composition the outer end of which is supported by a crossing column, which may be of quick-burning powder, lying in a cross channel at the end of the plug. The slow-burning column is 35 therefore supported against internal pressure and enables a complete gas tight enclosure to be obtained, within which is a movable pellet provided with small shearing lugs and a percussion cap.

40 When the shell is fired from the gun the shock of discharge breaks the small shearing lugs on the pellet and causes the latter to strike a projecting peg in the rear part of the fuse body. The percussion cap carried 45 in the pellet is thereby exploded and the flash passes through the center of the pellet and impinges on the inner end of the column of slow-burning composition. After a certain interval of time, the slow-burning 50 composition is consumed and the flame reaches the outer end of the plug and ignites the shell charge through the cross column of quick-burning powder.

In order that the said invention may be 55 clearly understood and readily carried into

effect I will now describe the same more fully with reference to the accompanying drawing, which shows in longitudinal section a fuse constructed in accordance with this invention.

60

A is the fuse body. B is a plug screwed into the inner end of the body and carrying the column b of slow-burning composition at the outer end of which is the cross column b' of the same composition, or of a quick burning powder, lying in the cross channel at the end of the plug. C is the pellet sleeve having the small shearing lugs c at one end lying against the shoulder a in the fuse body, the pellet being adapted to slide 65 in the chamber a' of the body. D is the percussion cap. E is the base of the shell to which the fuse is fitted.

70

The pellet illustrated comprises the sleeve C, screw threaded internally to receive the 75 two small plugs c', c''. Between the two plugs is the percussion cap D which is carried by the plug c' and bears against an extension of the plug c'', the latter being formed with the axial hole c''' for the passage of the flash from the percussion cap to the composition b. The sleeve C is held 80 from forward movement by the ring c'' interposed between the front surface of the sleeve and the plug B.

85

The body A of the fuse is provided with the internal peg F which effects the firing of the percussion cap when the shell is fired from the gun, the lugs c breaking off and allowing the plug to fly rearwardly so that 90 the cap strikes against the peg F and is fired. The flash from the percussion cap passes through the passage c''' and the forward end of the space or chamber a', reaching the rear end of the column b and slowly burning the 95 composition which burns until the cross column b', preferably of quick burning composition, is ignited when the main charge of the shell is fired.

Owing to the combustion taking place 100 under gas tight conditions, the fuse may be placed in the base, nose or any other convenient part of the shell. It is shown in the base E. The air space a' allowed within the fuse body is sufficiently large to prevent undue pressure from the combustion of the slow-burning composition. The columns b, b' of the composition may be replaced by a time setting device by which the effective length of the column can be varied, the pres- 105 110

ent invention not being restricted to any particular construction of fuse.

What I claim and desire to secure by Letters Patent of the United States is:—

5 1. In a shell fuse, a gas tight fuse body, firing mechanism contained in the said body, and a column of slow burning composition which forms a seal maintaining the fuse gas tight until the combustion of the said composition is advanced sufficiently to break 10 through and ignite the shell charge.

2. In a shell fuse, a gas tight fuse body, firing mechanism contained within the said body, a plug secured in the end of the body 15 having an axial channel and a communicating cross channel filled with columns of combustible which form a seal maintaining the fuse gas tight until the combustion of the axial and cross columns has advanced 20 sufficiently to break through and ignite the shell charge.

3. In a shell fuse, a gas tight fuse body, a plug secured in the inner end of the said body and provided with a channel filled with

slow burning composition forming a seal 25 maintaining the fuse gas tight, a pellet mounted in the fuse body and provided with a flash passage, a percussion cap on the pellet and a projecting member within the body adapted to meet the percussion cap on the shell being fired from the gun, the flash from the cap passing through the passage in the pellet to ignite the inner end of the column of the slow burning composition.

4. In a shell fuse, a gas tight fuse body, 35 firing mechanism contained within the said body, a plug screwed into one end of the body and provided with an axial passage and an external communicating cross channel, a column of slow burning composition 40 placed within the axial channel and a column of quick burning powder in the cross channel, the said columns forming a seal maintaining the fuse gas tight until combustion of the composition has advanced sufficiently to break through and ignite the quick burning powder and the shell charge.

FREDERICK GEOFFREY LEES JOHNSON.
